UNITED STATES PATENT OFFICE.

RUDOLF FÄNNER, OF VIENNA, AUSTRIA-HUNGARY.

DESIGN FOR A LUCKY FIGURE, AMULET, OR TALISMAN.

42,167.

Specification for Design.

Patented Feb. 13, 1912.

Application filed October 20, 1911. Serial No. 655,810. Term of patent 7 years.

To all whom it may concern:

Be it known that I, RUDOLF FÄNNER, a subject of the Emperor of Austria-Hungary, residing at 1 Stock im Eisenplatz 3, Vienna, Austria-Hungary, have invented a new, original, and ornamental Design for a Lucky Figure, Amulet, or Talisman, of which the following is a specification, reference being had to the accompanying drawing, forming part thereof.

I claim:

The ornamental design for a lucky-figure, amulet, or talisman, as shown.

RUDOLF FÄNNER.

Witnesses:

HANS PAPPENHEIM,
AUGUST FUGGER.
